CLAIM

The ornamental design for a percutaneous lead, as shown and described.

DESCRIPTION

FIG. 1 is a perspective view of a percutaneous lead according to our new design;

FIG. 2 is a side elevation thereof;

FIG. 3 is a top enlarged view thereof;

FIG. 4 is an enlarged view of area 4 circumscribed with dash-dot line within FIG. 1;

FIG. 5 is an enlarged view of area 5 circumscribed with dash-dot line within FIG. 1;

FIG. 6 is an enlarged view of area 6 circumscribed with dash-dot line within FIG. 2;

FIG. 7 is an enlarged view of area 7 circumscribed with dash-dot line within FIG. 2; and,

FIG. 8 is a perspective view thereof, shown in a position of use.

The dashed lines in form of a device shown in FIG. 8 depict environmental subject matter and form no part of the claimed design. All the other dashed lines in the drawings depict portions of the percutaneous lead that form no part of the claimed design. The short dash-long dash-short dash broken lines depict boundaries of the enlarged views that form no part of the claimed design.

1 Claim, 6 Drawing Sheets
